STEM FOR LIGHTING FIXTURES

Filed June 8, 1928

FIG. 3.

INVENTOR.

ALFRED E. DE KARSKE.

BY

Ralph W. Brown.

ATTORNEY.

UNITED STATES PATENT OFFICE.

ALFRED E. DE KARSKE, OF MILWAUKEE, WISCONSIN.

STEM FOR LIGHTING FIXTURES.

Application filed June 8, 1928. Serial No. 283,783.

This invention relates to stems for lighting fixtures.

The primary object of the invention is to provide a stem which is easily wired, readily adjustable in length, and adapted to serve equally well as a fixture hanger, body stem, or candle post.

A further object is the provision of an article to overcome breakage, misalignment, and cumbersome or inaccessible means for adjustability found in prior attempts to provide a suitable fixture stem.

Another object is the simplifying of the design of the stem to facilitate rapid installation or removal of lighting fixtures.

Other objects and advantages will appear from the following description of an illustrative embodiment of the present invention.

In the drawings:

20 Fig. 1 is a vertical midsection taken through a ceiling fixture positioned by a stem constructed in accordance with the present invention with parts broken away to more clearly illustrate its construction.

25 Fig. 2 is an enlarged sectional view taken on the line 2—2 of Fig. 1.

Fig. 3 is a front elevational view of the stem.

In an illustrative embodiment of the invention shown in the accompanying drawings, the stem comprises a body portion 10 adapted to be fixedly mounted to the outlet box in the usual manner, such as by threaded engagement with a coupling 11 carried by 30 the nipple on the outlet box. The lower portion of the body portion 10 is provided with a longitudinal slot 12. The edges of this slot are inwardly turned to form guide flanges 13. Diametrically opposite this slot 35 is an aperture 14, which is adapted to receive an inwardly turned lip 15 of a spring finger 16 which is fixedly mounted at its upper extremity to the outer wall of the body portion 10.

40 A second member 17 comprises the remaining portion of the stem. This member is fashioned to be slidably received within the body portion 10 and guided therein by the flanges 13 thereof. The portion 17 is

45 provided with a cut out portion or slot 18 extending longitudinally of the member to insure ready alignment of the two elements, and provide an aperture through which the wires may be threaded to be carried down to

55 the lights on the fixture. Diametrically opposite the slot 18 a series of perforations 19 are provided. These perforations 19 are adapted to register progressively with the aperture 14 in the body portion 10 as the member 17 is inserted therein and to permit 60 the entry of the lip 15 carried upon the lower extremity of the spring finger 16, to lock the two elements against outward movement. The lower extremity of the member 17 is provided with screw threading 20 upon 65 which an ornamental nut 22, fashioned in the form of a loop to carry a chain or the like, may be screwed to retain the fixture in position.

70 The mounting of a fixture by means of the present stem is extremely simple and effective as it eliminates the threading of the wires through the top of the stem which heretofore was the source of infinite trouble caused by the grounding of the wire which 75 had inadvertently been skinned while pulling the same downwardly through such a restricted opening.

70 To apply a fixture by means of the present stem it becomes necessary only to thread the 80 wires from the inside of the fixture through the aperture 24 at the lower extremity of the fixture 23. The wires are then threaded through the slot 18 in the member 17 and down through the lower extremity thereof. 85 The wires may then be threaded through the aperture in ornamental nut 22.

90 The ornamental nut 22 is then screwed part of the way onto the lower extremity of the member 17. The fixture may then be held against the ceiling in approximately 95 its proper position and the upper end of the member 17 inserted through the aperture 24 and positioned to register with the lower extremity of the body portion 10. When the ends of the elements 10 and 17 are in proper alignment the element 17 may be forced upwardly until the ornamental nut 22 bears against the bottom of the fixture 100 body to secure the same in place. The tip 105 15 of the spring finger 16 having come to rest in one of the series of perforations 19 to lock the elements in interengagement in that particular adjustment of the stem.

Should the lip 15 fail to register with a 105 perforation 19 on the member 17 it becomes necessary only to screw the ornamental nut 22 until the spring urged lip 15 snaps into

an adjacent perforation. Hence the nut 22 will readily serve as a micrometer adjustment between successive perforations.

While the foregoing description of the application of the present stem has been confined only to its use in connection with mounting the portion of a fixture abutting a wall or ceiling; without change of the stem proper it will serve equally well as stem for a body portion or canopy and also as a foundation for a candle stick on a fixture.

Should it become necessary to remove the fixture the operation requires only the removal of the ornamental nut and thus renders the fixture free from the ceiling without in any way altering the adjustment on the stem so that the fixture may be reapplied without change or readjustment of the stem.

While the invention has been described in considerable detail in the foregoing specification it is understood that various changes may be made in the embodiment of the invention without departing from or sacrificing any of the advantages as hereinafter claimed.

I claim:

1. An adjustable stem for lighting fixtures comprising a pair of hollow tubular members telescopically arranged to form a conductor conduit, a spring urged detent carried by one of said members, means on said second member cooperating with said spring urged detent to form a ratchet connection between said members to permit free collapse of the stem and effectively resist extension thereof from any of a plurality of positions of lengthwise adjustment said members may assume, and coacting guide

means on said members operable to insure coaction between said detent and said first named means.

2. An adjustable stem for lighting fixtures comprising a pair of telescopic members, a spring urged detent carried by one of said members, a slot in the wall of said member, guide means on said member, a slot in said second member cooperating with the slot and guide means in said first named member to prevent relative rotation between said members, a deformed portion on said second member cooperating with said spring urged detent to form a ratchet connection between said members to permit free collapse of said stem and effectively resist extension thereof from any of a plurality of positions of lengthwise adjustment therebetween.

3. An adjustable stem for lighting fixtures comprising a pair of telescopic members, a slot in one of said members, flanges on the other of said members cooperating with said slot to effectively prevent rotation of one member with respect to the other, a resilient detent carried by one of said members, a deformed portion on the other of said members registering with said resilient detent, said deformed portion and resilient detent forming in effect a ratchet engagement between said members to permit ready collapse of said stem and effectively lock the same against extension in any of a plurality of positions of lengthwise adjustment between said members.

In witness whereof, I hereunto subscribe my name this 5 day of June, 1928.

ALFRED E. DE KARSKE.
